UNITED STATES PATENT OFFICE.

WALTER BRAUNE, OF BERLIN, GERMANY.

DESIGN FOR AN ELECTRIC LAMP WITH SLIDABLE CONTACT-HANDLE.

45,832.

Specification for Design.

Patented May 26, 1914.

Application filed April 1, 1914. Serial No. 828,918. Term of patent 7 years.

To all whom it may concern:

Be it known that I, WALTER BRAUNE, subject of the German Emperor, residing at 15 Gneisenaustrasse, Berlin, Germany, have invented a new, original, and ornamental Design for an Electric Lamp with Slidable Contact-Handle, of which the following is a specification.

The figure is an elevation of an electric lamp with slidable contact handle showing my new design.

I claim:

The ornamental design for an electric lamp with slidable contact handle as shown.

In testimony whereof I have affixed my signature in presence of two witnesses.

WALTER BRAUNE.

Witnesses:

WOLDEMAR HAUPT,
HENRY HASPER.
